UNITED STATES PATENT OFFICE.

FLORENCE McCARTHY, OF NEW YORK, N. Y.

MAILING MACHINE.

Application filed March 30, 1920; Serial No. 369,851. Renewed January 14, 1926.

This invention is an improved machine for assembling envelopes and their enclosures, that is to say, a machine which may be termed for convenience a mailing machine, which inserts the enclosures into the envelopes and disposes the flaps. It is more particularly an improvement in the type of machine disclosed in my Patent 1,305,390, of June 3, 1919, wherein the envelopes and enclosures are contained in stacks in magazines at opposite sides, from the bottoms of which the envelopes and enclosures are alternately withdrawn and carried inward to the center by feed mechanism, and specifically by oppositely traveling belts, and at the center delivered downward to a loading station against a bottom stop, where each envelope stands to receive its enclosure, each loaded envelope being then carried longitudinally away from the loading station by conveying means, specifically by a longitudinally-traveling vertically-disposed belt and an opposed intermittently-actuated clutch or traction member, to the action of means whereby the flap is tucked in to the envelope over the enclosure or circular.

The object of the invention is to improve such machine both as to the whole and as to particular parts, as will become apparent as the specification proceeds. Among the more important features are: A novel construction of the magazines with automatically-actuated receding floors and pusher-floors and yielding stripper gates with flexible lips, whereby each bottom article drops and tilts forward with some weight onto the moving feed surface beneath and at the same time is pushed from the rear, so that its forward edge is caused to advance under the restraint of the yielding trailing gate, which holds back the superincumbent articles and furnishes traction pressure for the one in transit; a construction of the stripper gates, particularly of the enclosure magazine, with independent spring pressure adjusting means, whereby even feed and equal traction are obtained at the two ends irrespective of differences in thickness in the folded enclosure; means for adjusting the magazines for different lengths of envelopes and enclosures, and for centering the stacks; an automatic flap-opener or picker-finger moving toward and from the course of the envelope in front of the exit from the flap magazine, with means whereby the flap-opener bears

with yielding pressure; a forward traction member at the envelope side comprising a transverse yielding roller; an auxiliary traction member over the enclosure belt beyond the stripper gates of the enclosure magazine, whereby the middle of the enclosure is held flat upon the belt; a rearwardly hinged traction and feed-limiting plate floating on the forward part of the enclosure belt; a yielding baffle suspended in the slot between the proximate portions of the belts; convenient means for raising and lowering the bottom stop and its extension guide and holding the same for different depths of envelopes; means for buckling the face of each envelope at the loading station to spread its mouth for entrance of the enclosure; the baffle assisting; improved mechanism for automatically operating the clutch by which the loaded envelope is started from the loading station in time for the arrival of a fresh envelope; an opposed relation of the clutch to an inner support of the longitudinal belt, whereby the action of the clutch is prevented from stretching the belt; means whereby each loaded envelope is carried out along extended guiding and supporting means and released from the longitudinal belt at a flap-disposing station; means for adjusting the point of release of the rear end of the envelope, so that different lengths of envelope are centralized on the flap-disposing station; a novel automatically-operated overhanging flap inserter at said station comprising moving spreader and tucking fingers; an automatic kicker or ejector adjacent the inserter; the combinations and subcombinations of these instrumentalities and the operating connections driven from a common shaft or member, whereby the intermittently operating mechanisms are operated in timed relation.

The invention also comprises an arrangement whereby the flap inserter is convertible into a sealer, in conjunction with an attachable moistener. These and other features and aspects of the invention are embodied in the preferred form of machine herein illustrated and described and more particularly pointed out in the appended claims. In the accompanying drawings forming part hereof: Fig. 1 is a side elevation of the machine, Fig. 1 is a side elevation of the machine, looking at the back of the envelope maga-

zine and showing the machine organized for circular mail matter;

Fig. 2 is a fragmentary side elevation, looking at the same side of the machine, illustrating a conversion for operating upon first class matter;

Fig. 3 is a plan view, corresponding to Fig. 1;

Fig. 4 is a front end elevation corresponding to Fig. 1;

Fig. 5 is an enlarged vertical section taken approximately on the line 5—5 of Fig. 6, looking in at the region of the lower part of one of the magazines, the pusher floor and other parts being omitted for clearness of illustration and the intermediate part of the view being broken away for economy of space;

Fig. 6 is a vertical transverse section on the line 6—6 of Fig. 3, with the magazines broken away;

Fig. 7 is a vertical transverse section through the walls on the line 7—7 of Fig. 3, with the interior mechanism largely in elevation;

Fig. 8 is an enlarged vertical transverse section through the interior of the machine, showing the operating parts in two positions in full and dotted lines;

Fig. 9 is an enlarged vertical transverse section taken just outside the plane of Fig. 6, showing parts at the envelope-feeding side in two positions in full and dotted lines;

Fig. 10 is an enlarged vertical transverse section illustrating the parts seen in Fig. 7 at the envelope-feeding side in two operating positions;

Fig. 11 is an enlarged vertical transverse section of parts seen in Fig. 7, showing two operating positions;

Fig. 12 is a sectional plan view, corresponding to Fig. 11;

Figs. 13 and 14 are enlarged front end views illustrating the flap-inserting mechanism in different operating positions;

Fig. 15 is a front side elevation of the flap-inserting mechanism and the adjustable bottom guides with the support on which the inserter is mounted partly broken away;

Fig. 16 is an end view of the bottom guide and support;

Fig. 17 is a horizontal section on the line 17—17 of Fig. 13, illustrating the manner of removably supporting the spreading finger of the flap-inserter, upon removal of which the same is converted into a sealer;

Fig. 18 is a sectional plan view of parts adjacent the front end wall of the machine for operating the flap-inserter or sealer;

Fig. 19 is a front end view similar to

Figs. 13 and 14 but showing the machine organized for sealing the flaps, two operating positions being shown in full and dotted lines;

Fig. 20 is a plan view of the moistener seen in Figs. 2 and 19, portions thereof being broken away and sectioned; and

Fig. 21 is a plan view of the deflector used in connection with the moistener.

The frame of the machine comprises side walls 1, 1^a, which may incline inwardly and upwardly, as shown, and end walls 2, 2^a, together forming a boxed enclosure. The central portions of the end walls may be reinforced by external panels 3, 3^a. The end walls 2, 2^a at opposite sides of these central panels are bent inward to form ledges 4, 4^a, from which rise two pairs of vertical extensions 5, 5^a forming outer enclosure walls for two magazines, which are located at opposite sides of the machine and are designated generally 6, 6^a. The members of each pair of wall extensions 5, 5^a are adjacent what are termed, for convenience, the front and rear ends of the frame enclosure and form the exterior sides of the magazines, the contents of which are fed inwardly toward the longitudinal center. Consequently the inner sides of the magazines are to be regarded as their fronts and their outer sides as their backs.

The magazines 6 and 6^a are designed to hold stacks of folded paper sheet articles, envelopes within the magazine 6, and folded enclosures, either circulars or first class matter, within the magazine 6^a. The basal portions of two such stacks are diagrammatically indicated in Fig. 8, where it will be seen that the articles are held at a downward and inward inclination, with the front sides of the stacks substantially vertical against the front walls 7 and 7^a and the gates 8 and 8^a. The fixed front walls 7 and 7^a extend to within a suitable distance of the bottom, where they terminate, leaving forward basal exits 9 and 9^a (Fig. 7) which are guarded by the gates 8 and 8^a. The actual sides of the magazine or stack-holders are formed by pairs of vertical side plates 10, 10^a within the fixed side walls 5 and 5^a. The lower ends of these movable side plates 10, 10^a are guided upon the front walls 7, 7^a and are adjustable toward and from each other by

equal and opposite movements through the instrumentalities of shafts 12 and 12^a, the end portions of which are journaled and held against endwise movement in the fixed wall 5 and 5^a, outside of which they bear operating knobs 13, 13^a. The portions of each of said shafts at opposite sides of its center are screw-threaded in opposite directions, as indicated at 14 in Fig. 1, for engagement with correspondingly threaded nuts 15 carried by the pair of plates 10 or 10^a. Consequently rotation of the shaft in one direction causes the plates of the pair to approach, while rotation in the opposite direction separates them. In this way the magazines can be set for envelopes and enclosures of various

- lengths, and by the same means the stacks are automatically centered with respect to the mechanisms to which they are fed and by which they are operated upon. Straps 16 and 16^a tie the members of the pairs of fixed walls 5 and 5^a together at the tops, and the inner edges of these straps may be provided with notches 17 (Fig. 1) to indicate the different sizes.
- 10 The magazines have inwardly and downwardly inclined bottoms, whereon the stacks are supported, said bottoms being composed of floors 11, 11^a and 18, 18^a. In each magazine the floor 11 or 11^a is designed to support the forward part of the stack and is movable from a position where its forward edge is adjacent or projects somewhat outwardly at the bottom of the exit 9 or 9^a (see the left-hand side of Fig. 8) to a retracted position in which its forward edge is well back of the front line of the stack (see the right-hand side of the same view) and vice-versa. This floor will hereinafter be termed the forward receding floor, and in each magazine it is preferably supported and guided for straight sliding movement in its inclined plane. To this end channels 19, 19^a are fixed just within the main end walls 2, 2^a, beneath the ledges 4, 4^a, the channels of each pair facing inwardly toward each other and receiving the side edges of the sliding floor, (see Fig. 5).
- 15 The floor 18 or 18^a in each magazine supports the rear part of the stack and is adapted to advance as the forward floor recedes. It is hereinafter termed the rearward pusher-floor. Said pusher floors are inclined relatively to the receding floors, being arranged at a steeper angle, and their function is to advance the bottom article in the respective stacks while the receding floors withdraw, thus permitting the forward portion of such bottom articles to contact with the moving feed members herein-after described. The pusher-floors also serve to work the stacks so as to facilitate the withdrawal of the bottom articles. In order to assist them in advancing the articles, the pusher-floors are provided on their faces with a suitable number and arrangement of forwardly directed teeth or projections 200.
- 20 As an important feature of the operation of the pusher-floors means are provided whereby the angles of said floors change while advancing in a general forward and downward direction and retreating in a general upward and rearward direction. Thus, the angles of these floors lower as they advance and become steeper as they move backward, as indicated in Fig. 8. A simple embodiment of means for this purpose comprises a pair of links 20 or 20^a for each pusher-floor, the members of said pairs of links being pivoted by a fixed pivot 21 or 21^a and pivotally tied at 22 to lugs on the under sides of the pusher-floors adjacent their side edges. The links are so arranged as to swing from relatively erect to relatively forwardly inclined positions, and vice-versa, with a comparative- 70 short radius of movement, whereby the desired angular rise and fall of the pusher-floors is secured. The forward edges of these floors 18 or 18^a are most simply supported and guided by causing them to slide 75 upon a straight guide which is afforded by the receding floors 11 or 11^a.
- 25 Means are provided for effecting reverse operation of the receding and pusher-floors. The specific embodiment of such means may be varied, but in the preferred construction movement is imparted to the receding floors, and from them by a motion-reversing connection to the pusher-floors. As illustrated, the links 20 are extended downward to form levers, the lower portions of which ride upon the rear upper ends of the receding floors 11, 11^a. The latter are actuated by arms 23, 23^a on rock-shafts 24, 24^a, said arms bearing against suitable downward extensions 25, 25^a 90 on said floors. Thus, when the arms 23 or 23^a move rearwardly (with reference to the stacks) they withdraw the receding floors, and through the pressure of the latter upon the lever links 20 cause the pusher-floors to 95 advance. Springs 26, 26^a connected with the pusher-floors or with the levers 20, 20^a actuate the floors in the reverse directions, but it will be understood that the floors could be 100 positively operated in both directions if desired. The rock-shafts 24, 24^a are operated in proper time by pins 27, 27^a projecting endwise from cylinders 28, 28^a, said pins being arranged to encounter arms 29, 29^a 105 projecting from the shafts and to swing the same through a suitable arc of movement. When the pins ride from beneath these arms the rock-shafts and floors are returned to what may be termed the normal positions by the springs 26, as stated. There are prefer- 110 ably two or more of the arms 23 or 23^a to act upon each of the receding floors 11 or 11^a at laterally spaced points, and one of these arms may be formed as an integral bell-crank with the arm 29 or 29^a. 115
- 120 Beneath each of the magazines or the forward portion thereof is an endless belt 30 or 30^a, which passes about the large driven cylinder 28 or 28^a beneath the magazine and about a relatively small idle roller 31 or 31^a forwardly of the magazine and adjacent the vertical central longitudinal plane of the machine. These belts constitute embodiments of feed means for carrying the envelopes and enclosures inward to the center 125 and downward into a pocket or loading station, operating to this end in conjunction with other instrumentalities which will be described. The axes of the cylinders and rollers may be and preferably are substan- 130

tially in horizontal lateral alinement, and the arrangement is such that the upper courses of the belts travel inward and downward from the cylinders to the rollers at a substantial inclination, which is shown as being approximately the same as the inclination of the receding floors 11 or 11^a. The lower free courses of said belts are acted upon by tensioning rollers 32, 32^a on arms 33, 33^a pressed by springs 34, 34^a (Figs. 6 and 7). The inner guide rollers 31, 31^a are located close to each other at opposite sides of the central plane, and the interval between the belts 30, 30^a where they turn and pass down and around these rollers marks the top of the pocket where the loading is effected.

Power is applied to the machine for driving all of its coordinated mechanisms through a single shaft or power member, here represented by a shaft 35 supporting the roller 31 and free to turn therein, which shaft or an extension thereof projects through the rear end wall of the machine and bears a crank handle 36. For such handle, it will be understood, there may be substituted a pulley or other member for driving the machine from a motor. Said shaft and the corresponding shaft 35^a supporting the roller 31^a and the shafts or axles 37, 37^a of the cylinders 28, 28^a are journaled in suitable bearings in blocks 38 on the inner sides of the end walls 2 (see Figs. 1, 4, 5 and 18). The matter of providing suitable bearings and supports for shafts and rods occupying fixed positions, being of an obvious nature, will not be referred to in detail.

The driving shaft 35 bears a small spur gear 39 inside the rear end wall of the machine, said gear meshing with another similar gear 39^a on the shaft 35^a of the roller 31^a. These gears in turn mesh with idle gears 40, 40^a, through which they drive large gears 41, 41^a fixed on the axles 37, 37^a of the cylinders 28, 28^a. In this way the belts are driven constantly in opposite directions, their upper courses traveling inward and downward at equal speeds. The pins 27, 27^a heretofore referred to are upon the ends of the cylinders remote from the gearing just described, that is to say the ends of the cylinders which are inside the forward end wall of the machine, and by virtue of their connection with the cylinders are operated through the common driving mechanism. Said pins are placed at different angular positions with reference to the axes 37, 37^a, about which they revolve, so as to operate the compound floors of the two magazines alternately and in proper timed relation, their positions being such that each enclosure follows its envelope as quickly as may be down into the central pocket, where it enters the envelope.

65 The gates 8 and 8^a, previously mentioned,

will now be more particularly described. Each gate is shown as comprising two separate sections at opposite sides of the central portion of the exit 9 or 9^a, leaving such central region unobstructed (see Fig. 3). 70

The separate sections of each gate are of substantial width, so as to cooperate with the forward end portions of the envelopes and enclosures over a suitable extent thereof and so as to take in envelopes and enclosures of different lengths. Each section of each gate consists of a relatively rigid body 42 or 42^a composed of a pair of plates and a flexible lip 43 or 43^a of rubber, leather or the like, held by the rigid part and of 80 such length as to trail upon the belts 30, 30^a. The body parts 42, 42^a of the gate sections are hinged upon the rods 44, 44^a carried by the lower edges of the fixed front walls 7, 7^a of the magazines, the two sections of each gate being independently pivoted upon this rod so as to be capable of individual movement and adjustment. Each gate section is pressed inward against the face of its stack by a spring 45 or 45^a, and the pressure of these springs can be independently adjusted by thumbscrews 46, 46^a acting through levers 47, 47^a, which are swung upon the rods 44, 44^a independently 95 of the gates. The screws 46, 46^a have engagement with screw-threaded holes in said levers and bear at their extremities against the walls of the magazines. Consequently turning any one of the screws in one direction adds to the compression of its corresponding spring, and therefore to the downward and rearward pressure exerted by the corresponding lip 43 or 43^a. Conversely, turning the screw in the opposite direction 100 relieves such pressure to any degree desired. The lips themselves, while flexible, possess a substantial degree of stiffness and resilience. The hinging of the bodies of the gate sections is mainly for the purpose of adjusting the pressure, the major part of 105 the movement of the gates as the bottom articles are withdrawn from the stack taking place in the lips themselves. The independent adjustability of the sections of the gate is particularly important on the enclosure 110 magazine 6^a, as the enclosures will commonly consist of a sheet folded once in one direction and then twice in the other direction so that one end of the enclosure will be thicker than the other. In placing the enclosures in their magazine the thick ends should all be at the same side of the stack and the spring 45^a of the gate section at this side should be set with a lighter adjustment than 115 the spring of the other section. A common adjustment could be provided for the gate sections of the envelope magazines or a single continuous gate could be used on this magazine if desired. The function of the 120 gates presenting their trailing lips to the

125 gates presenting their trailing lips to the 130

feed members 30, 30^a is to strip the successive bottom articles from the stacks, that is to say to hold back the superincumbent articles while permitting the bottom one to advance out of the magazine, and at the same time to exert pressure upon such advancing article in opposition to the belt or feed member, so as to create traction.

At the enclosure magazine side an additional traction member 48 is provided between the sections 8^a of the gate for the purpose of holding the central part of the forward edge of the emerging enclosure against the belt, somewhat outwardly from or beyond the transverse region of pressure of the lips 43^a. Said member is shown as consisting of a finger mounted upon the central part of the rod 44^a and extending downward and forward, so that its trailing end rests upon the belt 30^a beyond and intermediate the lips, as stated. This member preferably exerts relatively light pressure, which is secured by means of a spring 49. This finger holds the central part of the enclosure flat upon the belt, and aids in the forwarding of the same to a traction plate 50.

Said plate 50 overlies the forward part of the upper course of the enclosure feed belt 30^a, extending from a region over and somewhat in rear of the roller 31^a at an inclination downward and forward and converging with that of the belt, and being curved at and adjacent its forward edge substantially in conformity with the curve of the belt where it passes around the upper forward quadrant of the roller. In the transverse direction the plate may be and preferably is substantially coextensive with the width of the belt. The plate is arranged to float upon the belt, resting thereon toward the front by gravity, with or without slight initial spring pressure, and to yield away from the belt against adjustable spring resistance to accommodate the passage of the enclosures between the same and the belt. In the simple and preferred construction illustrated the plate is pivotally supported at its rear portion, in order to maintain this portion at a sufficient separation from the belt to admit enclosures of any thickness and to permit the yielding of the forward part of the plate as stated. For this purpose the plate is provided at the rear and at opposite sides with hooked hinge lugs 51, engaging pins 52 projecting inward from the end walls 2 of the frame. A pair of rods 53 guided in lugs 54 on the inner sides of said walls have rounded lower ends whereby they are adapted to bear upon the top of the plate in advance of its hinge. A spring 55 encircling each rod between the upper guide lug 54 and a collar 56 fixed on the rod urges the latter downward to an extent limited by a thumb-nut 57. Said nuts are screwed upon the upper ends of the rods 53 above the upper lugs 54, and by turning them in one direction the rods can be lowered and the springs slightly relaxed, while turning them in the opposite direction raises the rods and slightly increases the compression of the springs. In this way the application of any substantial spring pressure through the plate to the belt while the plate is floating idly on the belt is avoided and the passage can be adjusted for different thicknesses of folded enclosures, so as to afford in each instance a degree of pressure while the articles are passing through which insures substantially positive traction without possibility of choking. The most effective driving grip exists between the forward curved part of the plate and the terminal region of the upper portion of the belt, which is here supported rigidly by the roller 31^a. When the rear edge of each enclosure passes beyond the forward edge of the plate, by which time it has been inserted downward into the waiting envelope, as will be more fully described hereafter, the driving effort exerted upon the envelope ceases, and accordingly the position of the front edge of the plate determines the extent of feed of the enclosures in the loading operation and therefore the height of the upper edges of the enclosures as they stand within their envelopes.

At the opposite or envelope magazine side of the machine the envelopes shortly after emerging from the magazine pass beneath a flap-opener 58, which has a movement toward and from the belt 30, being substantially separated therefrom in the absence of an envelope between them. Said flap-opener may consist advantageously of a rearwardly curved or hooked picker-finger, the upper end of which is pivotally supported on a shaft 59. Said shaft extends horizontally across the front of the envelope hopper, in front of its gates 42, and is journaled at its end portions in bearings 60 (Figs. 3 and 4) on the tops of the panels 3. From its support on the center of this shaft the finger curves outward and forward and thence downward and rearward, its free extremity being located forwardly of the vertical projection of its pivotal axis so as to have a movement toward and away from the belt substantially as indicated in Fig. 8. The flap-opener is operated periodically at the proper times by suitable connections from the operating mechanism of the machine, including a yielding connection whereby the finger when depressed is caused to bear upon the passing envelope with cushioned pressure, thereby both avoiding any possibility of injuring the envelope and affording a gentle traction pressure comparable to that of the finger 48 at the opposite side of the machine, such pressure being exerted at a point beyond the lips 43 of the gates, so as to aid in the forwarding of the envelopes.

In the particular construction illustrated (see Figs. 6 and 9) the gear 41 on the axle 37 of the belt cylinder 28 carries a pin 61 projecting toward the end of the cylinder, which in its revolution encounters and displaces the long depending arm of a lever 62, the upper portion of which passes through slots in the ledge 4 and in the parts beneath at the rear end of the machine, and is fulcrumed by a pivot pin 63 on stationary lugs 64. The short upper arm of this lever is connected by a helical spring 65 with a crank arm 66 on the rear end of the shaft 59. This spring serves as a yielding tension connection through which the lever when displaced by the pin draws the picker-finger 58 downward upon the back of a passing envelope, the proportions being such that the finger is held upon the envelope with cushioned pressure. Another spring 67, weaker than the spring 65, serves to withdraw the flap-opener upward and to restore the lever 62 to its normal position as soon as the pin 61 has passed beyond the long arm of the lever. The arching of the finger 58 and its spacing forwardly away from the magazine are such as to afford ample clearance for the rolling back of the flap. It is to be understood, of course, that the envelopes are placed in the envelope magazines with their backs and flaps facing upward and with their flaps at the rear and their closed bottom edges at the front. The movement of the flap-opening finger toward and from the belt 30 and the normal separation of the end of the finger from the belt permit the forward, bottom edge of each envelope to pass freely beneath the elevated finger, which if lowered at the time would catch the envelope and prevent its progress, and enables the finger to descend at a moment when it will intersect the edge of the flap approximately at the center and cause it to curl upward and backward substantially in the manner indicated in Fig. 9. The construction also avoids the finger bearing upon the belt in the absence of an envelope, which would cause undesirable wear. In general, it is to be observed, the nature of the gates, traction devices and flap-opener which cooperate with the envelopes and enclosures above the working courses of the belts 30 and 30^a is such as to secure the results intended without undue pressure and without the presentation of edges or points which might dig into the unprotected belts. Beyond the flap-opener 58 the successive envelopes still carried upon the belt 30 pass beneath a transverse traction roller 68 located above and somewhat rearwardly of the roller 31. This roller 68 extends substantially across the enclosure of the machine, from front to rear, and its journal ends are mounted in yielding spring-pressed bearings, whereby the roller automatically accommo-

dates itself to the passage of the envelopes. In the particular construction illustrated the roller has bearings 69 (Figs. 3 and 8) which are slidable in vertical guides 70 on the inner faces of the walls 2, springs 71 pressing upon the tops of the bearings to hold the roller gently and yieldingly down upon the belt.

At both sides of the machine it is desirable to support the upper courses of the belts 30 and 30^a in their stretches between the cylinders 28 and 28^a and the rollers 31 and 31^a, against the pressure of the devices above, and for this purpose one or more idle rollers 72, 72^a may be positioned beneath the belts in each of such intervals.

From the foregoing it will be understood that in the operation of the machine an envelope *a* is withdrawn from the bottom of the stack in the magazine 6 and carried inward and downward at an inclination on the belt 30, that its flap is opened in transit in this part of its course, and that where the belt turns and passes around the roller 31 the envelope is directed downward to a standing position, where it awaits its enclosure. It will also be understood that at an appropriate interval after the starting of the envelope upon such movement an enclosure *b* is withdrawn from the bottom of the stack in the magazine 6^a and started upon a similar, reverse course, and that the operating parts are so timed that the envelope reaches its receiving position somewhat before the enclosure has been advanced far enough to enter it. The time interval between the starting of an envelope and the starting of its enclosure upon their travel to the loading station is calculated with respect to the deepest sized envelope within the intended range of the machine. In the particular construction illustrated the timing is determined by the relative positions of the pins 27, 27^a in their orbits, while the timing of the flap-opener 58 is determined by the position of the pin 61 in its orbit. The extents of movement of the receding and pusher-floors 11, 11^a, 18, 18^a and of the flap-opener 58 and the length of time that they remain in their different positions are determined by the proportions of the operating connections, including the diameters of the several orbits and the extent of intersection of the paths of the pins by the arms 29, 29^a and the lever 62. As indicated, the relations are such that the floors are operated during a relatively brief period and remain for a relatively long period in their normal positions, that is to say with the receding floor forward and the pusher-floor retracted, while the flap-opener 58 is held down for a relatively brief, though substantial, period and elevated for a longer period. These matters are necessarily subject to variation by the mechanic, depending upon the

specific design and the closeness with which it is desired that the several operations shall follow each other, to the end of securing maximum output while avoiding possibility 5 of false operation.

The pocket between and below the proximate portions of the belts 30, 30^a, where the envelopes pause for loading, as herein advantageously constituted is defined at the 10 bottom by a vertically adjustable trough 73 and at the sides by walls 74, 75 and a belt 76. The trough 73 extends horizontally and longitudinally directly beneath and at approximate envelope-distance from the slot 15 between the belts. It is movable to different levels by virtue of handled dogs 77 on its under part projecting through slots 78, 78^a in the end walls 2, 2^a to cooperate with vertical ranges of holding notches 79 on the 20 outer faces of said walls, one of the dogs 77 being retractible against the resistance of a spring 80 (Fig. 1), so as to permit the trough to be moved up or down to a fresh position and there held. The trough thus constitutes 25 an adjustable bottom stop for the envelopes and it also forms a longitudinal guide extending lengthwise through the enclosure of the machine and outwardly through the slot 78 in the front end wall 2 and for a substantial 30 distance beyond the same, as seen in Figs. 1 and 17. The trough is thus spaced at varying distances below the relatively fixed sides of the pocket and its sides within the enclosure are inclined outward, as 35 seen in Figs. 6 and 7, to insure the seating of the lower edges of the successive envelopes. Where the trough passes through the front slot 78 its sides become vertical, and outwardly of this wall 2 one of its sides 40 disappears, so that the guide approximately becomes of the substantially right-angular form seen in Figs. 15 and 16, the purpose of which will become clear hereinafter.

The wall 74 is suitably supported within 45 the enclosure of the machine and extends horizontally substantially from end wall to end wall of such enclosure and vertically from a point close beneath the forward bend of the enclosure belt 30^a downward to within a suitable distance of the trough. 50 The opposite side wall 75 is preferably of similar longitudinal extent, and extends from a point close beneath the bend of the envelope belt 30 to the top of a longitudinal box or support 81, by which it is supported, the wall being substantially flush with and a continuation of the inner face of such box. 55 The box is appropriately fixed within the interior of the enclosure of the machine and projects outward through and beyond the front wall 2, as seen, for example, in Figs. 1 and 3. The box forms an enclosure and support for the longitudinal belt 76, which 60 passes about rear and forward end guide rollers 82 and 83 on vertical axes. The rear

roller 82 is located substantially midway between the end walls 2 of the enclosure, and therefore centrally with respect to the belts, 30, 30^a and the magazines 6, 6^a, which is important for reasons that will appear, while 70 the roller 83 is disposed within the projecting portion of the support at a point substantially rearward of its outer end. The inner working course of this belt is thus disposed vertically with respect to its transverse 75 dimension and substantially flush with the wall 75, the side of the box being open. The belt is continuously driven through a spur pinion 84 meshed by the gear 39 on the end of the roller 31, a suitably journaled longitudinal shaft 85 bearing said pinion 84 and a bevel gear 86 at the opposite end of said shaft meshing with a bevel gear 87 on the shaft 88 of the roller 82 (see Figs. 7, 11 and 12). The ratio is such that the longitudinal 85 belt 76 is driven at materially higher linear speed than the feed belts 30, 30^a. The belt 76 is tensioned by means of a spring 89 (Fig. 1) connected at its inner end to a yoke 90 slidable within the support 81 and 90 carrying the roller 83, the opposite end of said spring being connected to a movable end plate 91.

The loaded envelopes are pressed against the belt so as to be transported longitudinally from the pocket and outward along the projecting portions of the bottom guide 73 and support 81 by means of a periodically operated clutch 92. Said clutch preferably 100 comprises a lever 93 pivotally fulcrumed intermediate its ends at 94 on a fixed bracket 95 and bearing at one end a roller 96, which is adapted to be projected through an opening in the pocket wall 74 directly opposite the rear end belt roller 82. With these 105 regulations the roller 82 sustains the pressure of the roller 96 and prevents stretching of the belt 76. The clutch is urged toward the belt with yielding pressure by means of a spring 97. Means are provided for operating the clutch in proper timed relation with the other instrumentalities of the machine. Preferably detent means are provided for holding the clutch out of action away from the belt during the arrival of each envelope 110 and the entrance therein of its enclosure, together with means controlled by the driven operating mechanism of the machine for tripping or releasing the detent at the proper time to permit the spring 97 to throw the clutch into action and for subsequently retracting the clutch to be re-engaged and held by the detent. In the particular construction illustrated the end of the lever 93 remote from the roller 96 lies in front of a 115 slide 98, which is guided for longitudinal movement on a suitable support 99 at the inner side of and parallel with the front wall 2 of the machine enclosure. Said slide 120 is formed with one or more detent notches 125

100 for engagement by a detent dog 101, which is pivoted at 102 on said support. This detent is urged to holding position, wherein it prevents rearward movement of 5 the slide 98, by the action of a spring 103. Its upper end in said position lies in the path of the pin 27^a on the adjacent end of the cylinder 28^a. Said pin also encounters the upper end of a lever 105, which is pivotally fulcrumed intermediate its ends at 106 and connected at its lower end with the rear end of the slide 98 by a pivotal link 107. The relative positions are such that at the proper time in each revolution the pin 15 27^a presses against the detent 101, disengaging the same from the slide 98, which then no longer opposes the movement of the clutch lever 93 under the action of the spring 97, said spring accordingly throwing the 20 clutch from the broken line inactive position of Fig. 12 to the full line position and moving the slide from the dotted line position of Fig. 11 to the full line position of the same view. Thus the clutch is quickly 25 thrown in by its spring and held with yielding pressure. After a suitable interval, which is sufficient to cause the loaded envelope to be advanced to the influence of a subsequent traction member along the path of 30 longitudinal travel, the pin 27^a bears against the lever 105 and in its continued movement shifts the same, thereby resetting the slide 98 and the clutch 92, the clutch being withdrawn from the belt. In this operation the 35 detent 101 drops automatically into one of the notches 100 so as to hold the parts in the normal or unclutched condition until the next revolution of the pin. Said pin 27^a, it will be understood, is positioned at the 40 proper point in its orbit with reference to the other timing elements of the mechanism, so as to cause the clutch to move into action directly after but not before the envelope has been loaded.

45 Returning to the arrival of the envelopes and their enclosures at the top of the loading pocket, the presence should be noted of a longitudinal baffle plate 108 which hangs freely in the slot between the proximate 50 portions of the belts 30 and 30^a, being supported by hooked lugs 109 at the top and toward its end upon pins 110 projecting inward from the end walls 2, 2^a. This central baffle extends for a substantial distance 55 above the slot and for a short distance downward into the same, and serves to deflect the advancing edges of the envelopes and enclosures coming down the inclined belts 30, 30^a downward into the pocket. In 60 so doing it is free to yield alternately to right and left under the pressure of the articles, whereby the desired deflection is secured without possibility of choking. The 65 lower edge of the baffle is at such height as to clear the mouths of the envelopes when the latter stand upon the trough or adjustable bottom stop 73. At this point it may be noted that with the roller 68 over the envelope belt 30 located in the position shown, the tip of the flap of each envelope, 70 when the latter reaches the bottom stop 73, may still be held by the roller if the flap be a long one, or if a short one may be released so as to stand against the baffle, as seen in the drawings. The baffle 108 therefore 75 constitutes means for restraining the flap, as seen in Figs. 8 and 11, so as to leave the mouth of the envelope unobstructed, and as a longitudinal guide for this flap, so that when the envelope is transported lengthwise by the belt 76 the flap will pass out through the upper portion of the exit slot 78 in the front wall 2 in proper 80 position to be operated upon by the devices outside of this wall. The hooks 109 at the top of the baffle are open, so that the baffle can be lifted out off the pins 110, to permit of the removal of the contents of the loading pocket in event of a defective envelope or one with its flap stuck being fed from the stack.

85 The device which will be called the "knuckle" will now be described. This is an instrumentality for acting upon the face of the envelope, that is to say the side which receives the address, so as to buckle the same for the purpose of opening the mouth of the envelope to afford ready entrance for the arriving edge of the enclosure. The 90 knuckle is supported at the side of the loading pocket or station toward the envelope belt and at an appropriate distance below the slot between the proximate portions of the belt, and has operating connections, for actuating it at properly timed intervals in 95 the general action of the machine. In the particular construction illustrated the knuckle comprises a plate 111 pivotally hung upon the inner side of the wall 75, 100 near the top thereof, so that its free lower end or edge will act upon the face of the envelope a distance below the fold of the flap. In the longitudinal or horizontal direction the knuckle extends for a distance 105 sufficient to produce effective buckling. The connections for operating the knuckle include a yielding element, whereby it will give to the entrance of the enclosure into the envelope so that the enclosure will slip down into the envelope without binding. As with the other operating connections employed in the machine, the particular form 110 may, of course, be varied. In the preferred embodiment illustrated the end of the driven cylinder 28 adjacent the front of the machine carries an eccentrically located pin 27, heretofore referred to, and this pin in 115 the lower portion of its orbit encounters the tail of a bell-crank 112, which is pivotally 120 supported at 113 and urged contrary to 125 130

the action of the pin by a spring 114. A pin 115 on the other arm of the bell-crank bears upon an arm 116, which is secured to a shaft 117, which extends for a suitable distance over the top of the belt box 81 behind the wall 75, being supported in bearing lugs 118 on said box. At a suitable point said shaft bears an arm 119, the arms 116 and 119 with the shaft 117 constituting a bell-crank. The arm 119 is formed with an eye to work over a plunger rod 120, which passes through a suitable opening in the wall 75, and is connected at its forward end with the knuckle. A spring 121 encircles the rod 120 between a forward collar 122 on the rod and the arm 119. The spring 121 thus constitutes a yielding thrust connection between the arm 119 and the rod, which is connected to the knuckle. A cotter-pin 123 on the rear end of the rod 120 prevents disconnection and affords positive operation in withdrawal.

The bell-crank, 116, 117, 119 is urged in the direction to project the knuckle by a spring 124. The springs 114, 124 and 121 are of different strengths, the spring 114 being the strongest, the spring 124 next in strength, and the spring 121 being the weakest. Normally, that is to say when the pin 27 is off the bell-crank 112, the spring 114 holds this bell-crank in the dotted line position of Fig. 10, thereby holding the bell-crank 116, 117, 119 in its dotted line position against the action of the spring 124, and thereby in turn holding the rod 120 and the knuckle 111 drawn back against the wall 75 out of the way of an arriving envelope. When, however, the pin 27 rides upon the bell-crank 112, the latter is swung to the full line position in Fig. 10, thereby releasing the intermediate bell-crank to move under the action of its spring 124, which, acting through the yielding thrust connection 121, swings the knuckle out into the pocket against the face of the envelope. This position is preserved during the relatively brief period during which the pin 27 rides upon the tail of the bell-crank 112. At this time the enclosure *b* has been advanced by the belt 30°, so as to thrust its forward edge against the baffle 108, which is thereby swung toward the envelope side of the machine, as seen in Fig. 10. Thus, by the combined and opposite action of the knuckle and of the baffle, the latter pressing against the flap *c* under the action of the enclosure, the mouth of the envelope is effectually spread; and the forward edge of the enclosure, guided by the curved extremity of the plate 50 and deflected by the baffle 108 and then slipping along the base of the flap *c*, enters with certainty into the top of the envelope. The pin 27 now rides off the bell-crank 112 and the spring 114 quickly operates through the

intermediate connections to retract the knuckle so as to allow the enclosure to slip down the desired distance into the envelope. In order to insure against any binding of the enclosure in its movement into the envelope, the light yielding spring connection 121 is provided to permit the knuckle to give to the downward advance of the enclosure. From what has been said it will be understood that the timing of the knuckle is such that it is actuated almost directly after the bottoming of each envelope in the pocket and between this moment and the moment of arrival of the forward edge of the enclosure over the mouth of the envelope, and that the knuckle remains projected until after the enclosure has started into the mouth, and that immediately thereafter it is withdrawn to normal position. In some cases a yielding knuckle without operating connections might be employed, but it is more satisfactory to have it move to its work and then retreat out of the way.

Whereas the bottom stop or trough 73, which extended forms a bottom guide for conducting the loaded envelopes outside of the enclosure of the machine, is positionable at various heights for different depths of envelope, the forward lower edge of the traction and feed-limiting plate 50 over the enclosure belt 30° remains always at a fixed height which is so determined that the upper edges of the enclosures always project out of the mouths of the envelopes for a short distance up the inner faces of the standing flaps *c*, bridging the fold which connects the flaps with the fronts of the envelopes. This is important for subsequent operations. As soon as practicable after each enclosure has thus been introduced into its envelope, the clutch 92 heretofore described is brought into action, pressing the loaded envelope against the longitudinal belt 76 at a region where the latter is sustained by the roller 82, and the loaded envelope with the enclosure projecting and the flap usually standing erect and sliding along the baffle 108 is quickly transported endwise away from the loading station out through the exit 78 and upon the projecting guide 73a. As heretofore pointed out, the belt 76 is driven at much higher speed than the belts 30, 30°, the purpose being to remove each loaded envelope as expeditiously as possible, so as to clear the pocket or loading station sufficiently for the next envelope, which is already arriving.

The bottom guide 73 projects for a substantial distance forwardly from the front of the machine enclosure, as do also the belt box support 81 and the wall 75 which rises from the inner face thereof. The outer portion of the belt 76 terminates at a point in

termidate the front of the enclosure and the end of the support 81. As previously stated, the outer portion 73^a of the guide 73 consists simply of a bottom ledge and a single side flange 125 (Figs. 15 and 16), the said side flange being substantially beneath the face of the support 81 and the wall 75. Thus guiding and supporting means are provided for the bottom and for the front side of each loaded envelope as it approaches and comes to rest at a flap-disposing station. Mechanism, designated generally 126, is mounted upon the outer projecting part of the support 81 or its wall 75 for operating upon the flaps when the loaded envelopes arrive at the station; and in order to centralize envelopes of different lengths with respect to the station and the mechanism, means are provided for releasing the envelopes from the driving action of the belt at different points in the longitudinal direction. To this end a traction roller or member 127 is provided outside of the front of the enclosure of the magazine, in position to bear against the belt and the interposed envelopes, this roller being mounted adjustably. In the particular construction shown the roller is journaled in the end of a curved bar 128, which is slidable in a stationary housing 129 and provided upon its convex edge with notches 130 adapted for holding engagement with a pin 131 in the housing. A spring 132 is arranged so as both to hold the roller with yielding pressure against the belt and to retain the selected notch in engagement with the pin. It will thus be perceived that by moving the bar 128 laterally against the action of the spring and sliding it in one direction or the other, one or more notches, the position of the roller is shifted outward or inward along the active course of the belt 76. By the time the rear end of the envelope has left the grip of the roller 96, its forward end has come within the influence of the adjustable roller 127. As illustrated in Fig. 12, however, an additional intermediate traction roller 133 may be provided at a short distance inside the front end wall 2, in a fixed position where it will not obstruct the loading pocket, such roller adding to the certainty of driving and being useful for forwarding extra short envelopes.

The flap-disposing mechanism 126 is of a convertible character, in one instance serving to tuck in the flaps of envelopes containing circulars and in the other case operating to close the moistened flaps of envelopes containing first class matter.

The mechanism will first be described organized as a flap-inserter. Said inserter comprises one or more fingers, which enter the envelope between the back of the same and the enclosure to spread the envelope, and one or more fingers which then act to

tuck the flap in between the enclosure and the back of the envelope, together with suitable mechanism for periodically operating these fingers in time with the remainder of the machine.

A vertical plate 134 is held between spaced vertical posts 135 on the back of the outward extension of the wall 75, and between said wall and a back plate 136, which is secured to the posts 135 by screws 137. The plate 134 can be slipped upward out of the pocket thus formed, and when in position is held against displacement by a thumb-screw 138. A pair of laterally spaced arched horns 139 project laterally from the top of the plate 134 over the top of the wall 75 and outwardly from the face thereof, so as to overhang the flap-disposing station. A two-armed lever 140 lies intermediate these horns, being pivotally fulcrumed at 141 on the upper end of the plate 134. To the forward end of this lever is pivoted, at 142, the bifurcated end portion 143 of a central spreader finger 144, the blade of which is in obtuse angular relation to the portion 143 and slightly curved as shown. A pair of duplicate short links 145 are pivoted at their upper ends at 146 to the ends of the horns 139, and at their lower ends at 147 to the basal portion 143 of the spreader finger at a relatively short distance from the pivot 142. The lever 140 is urged by a spring 148 in a direction to elevate its forward end connected with the spreader finger. The rear end of said lever is bifurcated and carries a roll 149 to be acted upon by a cam finger 150, which is secured to a rockshaft 151, the action of the cam serving to depress the forward end of the lever while the spring raises it. Said rock-shaft also operates a pair of tucking fingers 152, spaced at opposite sides of the spreader finger 144. Said tucking fingers are pivoted at 153 upon the upper ends of the posts 135 and normally project over the top of the wall 75 and forwardly from the face thereof. A pair of duplicate links 154 are pivotally connected at 155 with the tucking fingers adjacent their pivots 153, and are operated by the rock-shaft 151. To this end the cam finger 150 is preferably provided with a cross-rod 156, the end portions of which project through longitudinal slots 157 in the links 154. Springs 158 constitute yielding connections between said cross-pin and said links. Consequently when the cam finger moves forward, the tucking fingers 152 are swung downward until their further movement is prevented by the lateral support afforded by the wall 75, whereupon the springs 158 yield to prevent injury.

The rock-shaft 151 is journaled in suitable bearings 159 on the posts 135, and thence extends rearward behind the wall 75 to and through the front end wall 2 of the

machine enclosure, where it finds another bearing, and at the inner side of said wall bears an arm 160 (Figs. 1, 7 and 18). The forward end portion of the driven shaft 35 which passes through the idle roller 31 of the envelope feed belt is located over the rear end of said shaft 151 and bears a spur gear 161, which meshes with another gear 162 rotatably supported at the inner side of the wall 2. Said gear 162 bears a pin 163, which periodically encounters the arm 160, so as to rock the shaft 151 in the direction to operate the inserter fingers from the full line position of Fig. 13 to the position of Fig. 14. A spring 164, coiled about the shaft 151 between the posts 135, acts to restore the parts quickly in the reverse direction when the pin 163 rides off the arm 160. The pin 163 and the arm 160 are so placed and proportioned with reference to each other and with reference to the other timing elements of the machine as to cause the operation of the inserter at the proper moment, that is to say shortly after a loaded envelope has arrived beneath the overhanging fingers under the propulsion of the belt 76 and has stopped there in substantially central relation to the fingers, owing to the rear end of the envelope having passed out from the influence of the adjustable traction roller 127.

As the loaded envelope *d* arrives at the flap-disposing station its upstanding flap crowding under the overhanging mechanism seen in Figs. 13 and 14 may cause it to topple away from the wall 75 against the support of the spreader finger 144, which is then in the normal outward position seen in Fig. 13. When the rock-shaft 151 is turned in counter-clockwise direction, as seen in Figs. 13 and 14, by the action of the pin 163 on the arm 160, the action of the cam finger 150 on the lever 140 flexes the toggle formed by the double link 145 and the portion 143 of the spreader finger 144, thus causing the finger 144, which is united with one member of the toggle, to swing upward and inward toward the lateral support 75, as represented by the dotted lines of Fig. 13. In so doing the tip of the finger rides up somewhat upon the back of the loaded envelope, passing above the lowest point of the top edge of the back, which may be approximately at the point marked "*x*" in Fig. 13, and pushing the envelope back toward the lateral support. At the same time the tucking fingers 152 are being swung downward through the links 154 and springs 158, thus starting to curl the flap over. As the movement of the rock-shaft continues, the further flexing of the toggle 143, 145, carrying the shifting fulcrum 147 of the spreader finger below the level of the center 146, causes the movement of the spreader finger to reverse, so that it moves downward and outward away from the wall 75. In so doing it slides down the exposed portion of the enclosure *b* and enters between the same and the back of the envelope, and as it continues to move outward widely spreads the mouth of the envelope, as seen in Fig. 14. At the same time the tucking fingers are continuing their movement downward and rearward toward the wall 75, thus folding the flap down and back into the envelope and over the enclosure. The enclosure by the same action is slid all the way down into the envelope. By reason of the upward projection of the enclosure above the fold of the flap, which results from the relations of the parts at the loading station as heretofore described, the spreader finger 144 cannot enter between the enclosure and the front of the envelope. The spring connections 158 prevent the tucking fingers 152 injuring the enclosure or the envelopes by exerting unyielding pressure upon them against the resistance of the wall 75, and avoid injury to the mechanism itself. With the parts in the approximate positions seen in Fig. 14, the next occurrence is the riding of the pin 163 off the arm 160 (Fig. 18), which permits the springs 164, 148 to snap the shaft 151 and the links, levers and fingers back to the normal or full line positions of Fig. 13. The movement of the shaft 151 in this direction is limited by stop shoulders 201 (Fig. 13) cooperating with the fingers 152. This stop is so arranged as to prevent either of the sets of centers 153, 155 and 156 or 142, 146 and 147 to come into line. The resulting rearward and upward movement of the spreader finger 144 tends to carry it out of the envelope and to permit the same to close.

At the same time a kicker or ejector 165 comes into action to throw the envelope off the ledge 73. Said kicker is automatically operated from the rock-shaft 151 upon the impulsive spring-operated movement thereof, and is preferably constituted by an arm which is pivoted at 166 behind the wall 75 adjacent and below the inserter mechanism, the finger passing outward through an opening in the wall and then normally extending straight downward against the face of the wall for a substantial distance. The kicker has a rearward projecting tail 167 with a step 168 to cooperate with a dog 169, which is pivoted at 170 on a hub 171 fixed to the end of the rock-shaft. The relations are such, as seen in Fig. 13, that the dog normally hangs down behind the step 168. As the rock-shaft is operated to actuate the fingers 144 and 152 to the positions shown in Fig. 14, the dog 169 is elevated and swings in over the step. Consequently when the shaft is turned backward by its spring after the insertion of the flap, the kicker is thrown sharply outward to the dotted line position of Fig. 14, thereby discharging the envelope.

The operation of the machine as now described will be reviewed. Stacks of envelopes and enclosures are placed in the magazines 6 and 6^a, respectively, the components of the stacks inclining downward and forward against the front walls of the magazines and their basal gates 8, 8^a, and being downwardly bowed by reason of the angular relation of the receding and pusher-floors. All of the envelopes have their flaps and backs uppermost, with the flaps at the back of the stack and their closed bottom edges at the front. The machine is then set in operation by power applied by hand or otherwise to the common driving member, represented by the handle 36, which is connected in this instance with the axis of the roller 31 of the envelope belt. Through the meshing gears 39, 39^a, 40, 40^a and 41, 41^a, the cylinders and rollers of the envelope and enclosure feed belts 30 and 30^a are set in motion, causing the inclined upper courses of the belts to travel inward and downward from beneath the magazines at opposite sides to the approximate center of the machine, where they turn around the rollers 31, 31^a, leaving a slot through which the envelopes and enclosures are passed vertically downward into the loading pocket. It will be assumed that the pin 27 of the cylinder 28 of the envelope belt first encounters the arm 29, through which the arms 23 are swung to actuate the receding and pusher-floors 11 and 18 of the envelope hopper. The receding floor slides backward, permitting the forward portion of the bottom envelope to rest upon the traveling belt, and at the same time the pusher-floor moves forward and downward, lowering its angles as it advances and thereby compelling the forward, bottom edge of the envelope to pass out beneath the restraint of the trailing lips 43 of the gate. These lips hold back the envelopes above and supply a certain traction pressure to the emerging envelope which causes it to be carried on by the belt. The floors, having initiated the withdrawals of the bottom envelope, are restored to their normal positions by the springs 26, the pin 27 having passed away from the arm 29. The envelope continues to advance on the belt, and its forward edge passes under the flap-opening finger 58, which at this time is in its raised position. Almost immediately after the leading edge of the envelope arrives beneath the said finger, the pin 61 on the gear 41 is brought against the lever 62, which through the spring connection 65, the arm 66 and the rock-shaft 59 swings the finger down upon the back of the envelope in front of the approaching flap. The parts are so proportioned that the spring 65 is somewhat tensioned while the spring 61 continues to ride upon the arm 62 so as to hold the opening finger down with an impositive pressure which does not injure the envelope or interfere with its progress and which does contribute to the tractive effect of the belt. The forward part of the envelope next passes beneath the yieldingly spring-pressed traction roller 68 and then strikes against the freely suspended baffle 54, which yields to its thrust and directs it substantially vertically downward around the bend of the belt and between the walls 74 and 75. At about the time when the envelope is first being deflected by the baffle, the point of the flap *c* reaches the tip of the opening finger and rolls up upon the internal curve thereon and springs backward to the space between the finger and the gate, as seen in Fig. 9. The progress of the envelope thus far is illustrated in Figs. 8 and 9. As the envelope continues to pass down into the loading pocket, the pin 61 recedes from the lever 62, permitting the spring 67 to raise the flap-opening finger, so that it will not obstruct the forward edge of the envelope next to be fed from the magazine. The envelope continues to be driven by the cooperative action of the belt 30 and the roller 68 until the point of the flap passes out from under the roller or is held only by its tip, depending upon the length of the flap. The envelope then bottoms upon the trough 73, which has previously been adjusted vertically for this particular depth of envelope.

Turning now to the enclosure side, it will be understood that at a suitable interval after the floors of the envelope magazine were actuated by the pin 27 and then returned to normal position by the spring 26, the floors of the enclosure magazine were similarly operated from the pin 27^a. This started an enclosure on its travel to the loading station, while the envelope was in the latter part of its progress to the same destination. The interval between the starting of an envelope from its magazine and the starting of the enclosure from the other magazine is calculated so as to be sufficient to permit the largest size of envelope within the range of the machine to reach the adjustable bottom stop before the leading edge of the enclosure reaches its mouth. The importance of the relative adjustability of the pressures of the sections of the gate 8^a of the enclosure magazine in securing an even feed of the enclosures, notwithstanding differences in thickness at opposite ends thereof, has already been mentioned. After passing out from beneath the lips 43^a of these sections the central portion of the forward edge of the enclosure moves beneath the trailing finger 48, by which light pressure is applied to aid in the traction and to hold flat this part of the enclosure, which if of thin material might curl and catch against the rear part of the traction and feed-limiting plate

50. By the time the envelope has reached its waiting position erect upon the bottom stop 73, the forward portion of the enclosure is passing beneath said plate, which yields 5 to accommodate its thickness, and thereby through the springs 55 applies sufficient pressure against the support of the roller 31^a to complete the feeding of the enclosure. The edge of the enclosure is initially guided 10 downward into the slot by the curvature of the forward lip of the plate 50 and then by the deflecting action of the baffle 108. At or shortly before this moment, the pin 27 has acted upon the lever 112, so as to cause the 15 knuckle 111 to be projected against the front face of the waiting envelope, a short distance below the base of the flap, so as to buckle the envelope from this side, while the flap is simultaneously forced backward by 20 the pressure of the enclosure against the baffle, as seen in Fig. 10; thereby the mouth of the envelope is held open directly beneath the advancing edge of the enclosure, which then commences to enter the envelope. By 25 virtue of the spring 120, as heretofore explained, the knuckle is made capable of yielding, so that the passage of the enclosure into the envelope is not opposed. The period during which the knuckle is held projected is very brief, and when it has performed its function it moves back out of the way. The enclosure continues to be passed into the envelope until its rear edge leaves the forward edge of the plate 50. 30 The enclosure may settle a slight distance farther by gravity and momentum, but practically speaking, the location of said edge of the plate determines the limit of insertion and leaves the upper portion of the enclosure projecting from the mouth and above the fold of the flap, as represented in Fig. 8.

Next the pin 27^a strikes the detent 101 (Figs. 7, 11 and 12) disengaging the same 45 and causing the spring 97 to throw the clutch roller 96 against the loaded envelope, pressing the same against the fast-traveling longitudinal belt 76. Thereupon the envelope is rapidly carried forward out of the 50 pocket along the guide trough 73. Shortly thereafter, by which time the envelope has come within the influence of one of the succeeding traction devices 133, 127, the pin 27^a strikes and swings the lever 105, thereby 55 through the slide 98 withdrawing the clutch from the loading pocket and causing it to be withheld by the automatic re-engagement of the detent 101. The envelope passes out of the front of the enclosure of the magazine 60 through the slot 78, its bottom edge sliding upon the guide 73. Through the cooperation of the adjustable traction roller 27 with the belt it is carried upward along said guide and its extension 73^a to a definite position, 65 where it is no longer driven, and stands be-

neath the overhanging inserter illustrated more particularly in Figs. 13, 14 and 15. By appropriate adjustment of the roller 127, the envelopes, according to their length, are caused to stop substantially centrally beneath this mechanism. At about the time of the arrival of the loaded envelope at this station or very shortly thereafter, the pin 163 (Figs. 1, 7 and 18) rides up under the 70 arm 160 on the rear inner end of the rock-shaft 151 and turns this shaft through an arc sufficient to cause the spreading and tucking fingers 144, 152 to pass from the normal positions shown in Fig. 13 to the final positions seen in Fig. 14, where the envelope 75 is spread and the flap tucked in. The operation of these parts has been recently described and will not be repeated. Thereafter the pin 163 passes away from the arm 160 and the springs 164 and 148 restore the 80 fingers to the normal position, the spring 164 at the same time throwing forward the kicker 165, so as to displace the loaded and tucked envelope off the support 73^a. The 85 cycle of operations is continuously repeated, the envelopes and enclosures following through the machine in close succession. While one envelope is being loaded at the loading station beneath the slot between the 90 belts 30, 30^a, another envelope is being started from the envelope magazine, and while the loaded envelope is being carried longitudinally out of the loading station the succeeding envelope is entering said station, shortly thereafter receives its enclosure and 95 follows in its turn. Each empty envelope coming down into the loading station somewhat overlaps the preceding loaded envelope, which is moving horizontally out of the station. This takes place without choking the 100 loading station and time is saved, since the envelopes would have to be fed substantially slower if it were necessary for the loaded envelope completely to clear the station before the next empty one arrived. The knuckle 105 and the flap-inserter are preferably timed so as to operate substantially simultaneously, that is to say an envelope is being loaded at the loading station while a preceding loaded envelope is having its flap inserted or 110 folded at the flap-disposing station. The 115 adaptation of the machine for loading and sealing first-class matter will now be described. The loading mechanism and its operation are precisely as before. At the flap-disposing station, however, the thumbscrew 138 is loosened and the plate 134 carrying the lever 140, the horns 139, the spreading finger 144 and the links 145 is lifted out. As the cam finger 150 is not tied to the lever 140, but merely bears against the same, this removal can be effected without taking any part of the mechanism to pieces, and conversely these parts are restored to operative position and relation by 120 125 130

- merely slipping in their plate and tightening the screw. The condition with the said parts removed is illustrated in Fig. 19. The fingers 152 remain but they now constituting 5 folding and pinching members for turning the flap down on the back of the envelope and applying a sealing pressure. When the machine is used in this way, a moistener 171 is applied to the front of the enclosure of 10 the machine, to wet the gummed sides of the upstanding flaps of the envelopes before they pass beneath the fingers 152. This moistener comprises a suitable tank having a rear flange 172 to overlie the top of the 15 front panel 19, downward projecting studs 173 on said flange entering sockets 174 in the panel. A wick strip 175 is held in a slot in the side of the tank adjacent the exit 78, through which the flaps *c* must pass. This 20 wick strip presents a vertical edge, preferably forwardly inclined in the direction of travel, as seen in Fig. 20, and in connection therewith a deflector 176 is provided for compelling the flaps to wipe against the 25 wick. Said deflector may comprise a vertical plate having reversely laterally inclined rear and front lips 177 and 178 and a bridge 179 with an upturned end flange 180. The said bridge is slipped in between the top of 30 the tank and a keeper 181, which latter is slotted at 182 to receive the flange 180. As thus held in position the vertical body of the deflector 176 is supported close to the edge of the wick, while the rear lip 177 flares 35 across the upper part of the exit 78, as shown in Fig. 19, to gather in the flap and bring it to the wick, the forward lip 178 giving the flap an additional deflection in the same direction so as further to compel an effective 40 wiping engagement. In this way the gum on each flap is moistened, and immediately after leaving the moistener the flap arrives beneath the fingers 152, which are thereupon actuated to fold the flap down upon the 45 back. The kicker then operates in the same manner as in the case of the flap-inserter, and the envelopes may then be passed between rollers, not shown, to insure complete sealing.
- 50 What I claim as new is:
1. In a machine of the character described, an envelope magazine, means for advancing envelopes successively from said magazine with the bottom of each envelope to the 55 front, a flap-opener comprising a picker finger hinged adjacent the front of the magazine and extending therefrom at a distance from the course of the envelopes and deflected toward its tip into proximity to said course, and means for periodically oscillating the picker finger.
  2. In a mailing machine, the combination of envelope and enclosure magazines at opposite sides, belts traveling inward into 60 proximity to each other and turning down-

ward, means for supporting the envelopes upright in a pocket between the belts to receive the enclosures, and an intermediate baffle plate.

3. In a mailing machine, the combination 70 of envelope and enclosure magazines at opposite sides, belts traveling inward into proximity to each other and turning downward, means for supporting the envelopes upright in a pocket between the belts to receive the enclosures, and an intermediate 75 baffle plate, said baffle plate being yielding.

4. In a mailing machine, the combination 80 of envelope and enclosure magazines at opposite sides, means for feeding the envelopes and enclosures alternately inward and downward, means for supporting the envelopes upright in a pocket to receive the enclosures, and a baffle plate freely suspended 85 above the pocket.

5. In a machine having envelope and enclosure magazines at opposite sides, means for feeding the envelopes and enclosures alternately inward and then downward to a central pocket where the successive envelopes stand to receive their enclosures, a central swinging baffle plate, and means supporting said plate and permitting it to be 90 lifted out.

6. In a machine of the character described, 95 the combination of envelope and enclosure magazines at opposite sides, means for feeding the envelopes and enclosure alternately inward and then downward to a central pocket where the successive envelopes stand to receive their enclosures, and a central 100 baffle plate.

7. In a machine of the character described, the combination with envelope and enclosure 105 magazines at opposite sides, and means for feeding the envelopes and enclosures alternately inward and then downward to a central pocket where the successive envelopes stand to receive their enclosures, of a central 110 yielding baffle plate.

8. In a mailing machine, the combination 115 of envelope and enclosure magazines at opposite sides, means for feeding the envelopes and enclosures alternately inward and downward, a bottom stop, a side wall guide extending downward from the interval at the side opposite the envelope feeding means, and an intermediate baffle above.

9. In a mailing machine, the combination 120 of envelope and enclosure magazines at opposite sides, means for feeding the envelopes and enclosures alternately inward and downward, means defining a pocket wherein the envelopes are supported upright to receive the enclosures, said pocket having two side walls and a bottom, means for moving the filled envelopes longitudinally from the pocket, and an intermediate baffle plate 125 above the pocket.

10. In a machine of the character de- 130

- scribed, the combination of envelope and enclosure magazines at opposite sides, means for feeding the envelopes and enclosures inward and then downward to a central pocket 5 where the successive envelopes stand to receive their enclosures, means for turning the flaps of the envelopes on their way to the pocket, and a central baffle plate.
11. In a machine of the character described, the combination of envelope and enclosure magazines at opposite sides, means for feeding the envelopes and enclosures inward and then downward to a central pocket where the successive envelopes stand to receive their enclosures, means for turning the flaps of the envelopes on their way to the pocket, and a central baffle plate, the relations being such that the flaps stand against the baffle plate.
12. In a machine of the character described, the combination of envelope and enclosure magazines at opposite sides, means for feeding the envelopes and enclosures inward and then downward to a central pocket 25 where the successive envelopes stand to receive their enclosures, means for turning the flaps of the envelopes on their way to the pocket, a central baffle plate, and means for moving the loaded envelopes longitudinally from said pocket, the relations being such that the flaps stand against the baffle plate, which acts as a guide therefor in respect to the longitudinal movement.
13. In a machine of the character described, the combination of envelope and enclosure magazines at opposite sides, means for feeding the envelopes and enclosures inward and then downward to a central pocket where the successive envelopes stand to receive their enclosures, means for turning the flaps of the envelopes on their way to the pocket, a central baffle plate, means for moving the loaded envelopes longitudinally 40 from said pocket, the relations being such that the flaps stand against the baffle plate, which acts as a guide therefor in respect to the longitudinal movement, and means for subsequently acting upon the flaps, to which the flaps are thus guided.
14. The combination of an envelope magazine, means for feeding the envelopes therefrom in a generally horizontal direction and then downward in a continuous course to a loading stop, and a yielding baffle at the region where the envelopes change their direction.
15. The combination of an envelope magazine, means for feeding the envelopes therefrom in a generally horizontal direction and then downward in a continuous course to a loading stop, and a swinging baffle plate suspended over the region where the envelopes change their direction and move downward to the loading stop.
16. In means for loading envelopes, 65 means for supporting the envelopes and restraining their flaps while receiving their enclosures, and a knuckle operative against the fronts of the envelopes, while thus stationarily supported, to open their mouths. 70
17. In a mailing machine, the combination with envelope and enclosure magazines at opposite sides and belts traveling inward and turning downward, of a baffle in the interval above, means to sustain the envelopes in upright position below with their flaps against the baffle, and a knuckle operative against the fronts of the envelopes while thus sustained to open their mouths for reception of 75 the enclosures.
18. In a mailing machine, the combination with envelope and enclosure magazines at opposite sides, and means for feeding the envelopes and enclosures alternately inward and then downward to a central pocket 80 where the successive envelopes stand to receive their enclosures, of a central yielding baffle, means for opening the flaps of the envelopes and releasing the same to stand against said baffle, and a knuckle operative 85 against the fronts of the envelopes while awaiting their enclosures, whereby the mouths of the envelopes are opened for entrance of the enclosures by the combined and opposite action of the knuckle and baffle, 90 the latter yielding to the contact of the enclosure.
19. In a mailing machine, the combination with envelope and enclosure magazines at opposite sides, and means for feeding the envelopes and enclosures inward and then downward to a central pocket where the successive envelopes stand to receive their enclosures, of a knuckle at one side of the 100 pocket to act upon the fronts of the envelopes to open their mouths, and mechanism for periodically operating said knuckle.
20. In a mailing machine, the combination with envelope and enclosure magazines at opposite sides, and means for feeding the envelopes and enclosures inward and then downward to a central pocket where the successive envelopes stand to receive their enclosures, of a knuckle at one side of the 110 pocket to act upon the fronts of the envelopes to open their mouths, said knuckle comprising a hinged plate paralleling the pocket at the side of the envelope belt, and mechanism for periodically projecting the 115 knuckle for a brief period.
21. In a machine of the character described, the combination with means for successively and alternately moving envelopes and enclosures to a loading station, of a 120 knuckle arranged to act upon the fronts of the envelopes at said station to open their mouths for the entrance of the enclosures,

- means for periodically operating the knuckle and a yielding connection whereby the knuckle may give to an enclosure to prevent binding.
22. In a mailing machine, the combination of a loading stop, means for moving envelopes transverse to their flaps and with their lower edges in advance against said stop, means acting upon one face of envelopes to drive them frictionally to and into the envelopes as they rest against said stop, means whereby the stop can be shifted with or against the direction of advance of the envelopes, and a traction device cooperative with the other face of the enclosures and adapted to release the rear edges of the enclosures at a fixed point after the enclosures have entered the envelopes irrespective of the position of the stop.
23. In a machine of the character described, the combination with envelope and enclosure magazines, and means for successively and alternately moving the envelopes and enclosures to a loading station, of an adjustable stop for the bottom edges of the envelopes at such station, means for limiting the feed of the enclosures so as to insert them in the envelopes with their upper edges projecting at a fixed height irrespective of the height of the bottom stop, means for conveying the envelopes longitudinally from said station, and flap inserting mechanism at a farther station including finger means adapted to ride upon the projecting enclosures into the envelopes to spread the same.
24. In a machine of the character described, a flap inserter comprising an entering body-spreading finger which operates within the envelope and tucking fingers, and mechanism for operating said fingers, substantially as set forth.
25. In a machine of the character described, the combination of means for inserting an enclosure into an envelope with the enclosure projecting so as to bridge the fold of the flap, means for conveying the loaded envelope to a flap-inserter, and a flap-inserter comprising an entering body-spreading finger which rides on the projecting enclosure, and tucking fingers, with operating mechanism, substantially as set forth.
26. The combination of means for conveying a loaded envelope longitudinally to a flap-inserting station, a support for the front of the envelope at said station, horns projecting from the support, an operating lever, a body-spreading finger connected by compound linkage with said horns and lever, and flap-tucking fingers, substantially as set forth.
27. In a machine of the character described, flap-inserting and ejecting means, comprising a shaft, driving mechanism for periodically operating said shaft forward and spring means for restoring it, body-spreading and flap-tucking fingers operatively connected with said shaft for operation on the forward movement thereof, and a kicker actuated thereby on the reverse movement under the sudden action of the spring.
28. The combination with body-spreading and flap-tucking fingers, with a shaft periodically driven in one direction and spring actuated in the other, of a kicker, and a dog connected with the shaft to actuate the kicker on the return movement of the shaft.
29. The combination with body-spreading and flap-tucking fingers, with a shaft periodically driven in one direction and spring actuated in the other, of a pivoted kicker having a tail, and a pivoted dog eccentrically connected with the shaft to cooperate with said tail.
30. In a mailing machine, the combination with an upright belt for conveying loaded envelopes longitudinally to a flap-disposing station, of means comprising a body-spreader and a flap-tucker overhanging said station, and operating mechanism, the body-spreader being removable in order that the flap-tucker may operate to press the flap against the body.
31. In a mailing machine, means for disposing the flap, comprising a body-spreader and a flap-tucker, with operating mechanism for both, and means whereby the spreader can be lifted out.
32. In a mailing machine, the combination of a longitudinal guide affording support for the bottom edges and front sides of the loaded envelopes and driving means for moving the envelopes along said guide to a station, and flap-manipulating finger mechanism operative at said station.
33. In a mailing machine, the combination of a longitudinal guide affording support for the bottom edges and front sides of the loaded envelopes and driving means adapted to move the envelopes along said guide to a station and there release them, and flap-inserting finger mechanism overhanging said station, comprising spreading and tucking fingers.
34. In a mailing machine, the combination of a longitudinal guide affording support for the bottom edges and front sides of the loaded envelopes and driving means for moving the envelopes along said guide to a station, flap-manipulating finger mechanism operative at said station, and a device also operative at the station to displace the envelopes off the support.
35. In a mailing machine, the combination of an envelope magazine, movable floor mechanism for said magazine for starting the successive envelopes on their course, a flap-opener movable toward and from the

- course of the envelopes, and driving means and operating connections for periodically operating said floor mechanism and flap-opener in timed relation.
36. In a mailing machine, the combination of envelope and enclosure magazines, movable floor mechanisms for said magazines whereby the envelopes and enclosures are started alternately on their courses, means for conveying the envelopes and enclosures to a loading station, a knuckle for opening the mouth of each envelope at the loading station, and driving means and operating connections for operating said floor mechanisms and knuckle in timed relation.
37. In a mailing machine, the combination of envelope and enclosure magazines, movable floor mechanisms for said magazines whereby the envelopes and enclosures are started alternately on their courses, means for conveying the envelopes and enclosures to a loading station, a flap-opener movable toward and from the course of the envelopes and mechanism, a knuckle for opening the mouth of each envelope at the loading station, and driving means and operating connections for operating said floor mechanisms, flap-opener and knuckle in timed relation.
38. In a mailing machine, the combination of envelope and enclosure magazines, movable floor mechanisms for said magazines for starting the envelopes and enclosures alternately on their courses, means for conveying the same to a loading station, a flap-opener movable toward and from the course of the envelopes, a knuckle at the loading station for opening the mouths of the successive envelopes, means for conveying the loaded envelopes longitudinally from the loading station, movable mechanism thereafter operating upon the flaps of the envelopes, and driving means and operating connections for operating said floor mechanisms, flap-opener, knuckle and flap mechanism in timed relation.
39. In a mailing machine, the combination of envelope and enclosure magazines, movable floor mechanisms for said magazines for starting the envelopes and enclosures alternately on their courses, means for conveying the same to a loading station, a flap-opener movable toward and from the course of the envelopes, a knuckle at the loading station for opening the mouths of the successive envelopes, means for conveying the loaded envelopes longitudinally from the loading station to a flap-inserting station, an inserter at said station comprising spreading and tucking fingers, and driving means and operating connections for operating said floor mechanisms, flap-opener, flap mechanism and inserter in timed relation.
40. In a mailing machine, the combination of envelope and enclosure magazines, movable floor mechanisms for said magazines whereby the envelopes and enclosures are started alternately on their courses, means for conveying the envelopes and enclosures to a loading station, a flap-opener movable toward and from the course of the envelopes and mechanism, a knuckle for opening the mouth of each envelope at the loading station, and driving means and operating connections for operating said floor mechanisms and flap-opener in timed relation.
41. In a mailing machine, the combination of envelope and enclosure magazines, movable floor mechanisms for said magazines whereby the envelopes and enclosures are started alternately on their courses, means for conveying the envelopes and enclosures to a loading station, a flap-opener movable toward and from the course of the envelopes and mechanism, and driving means and operating connections for operating said floor mechanisms and flap-opener in timed relation.
42. In a mailing machine, the combination of envelope and enclosure magazines, movable floor mechanisms for said magazines for starting the envelopes and enclosures alternately on their courses, means for conveying the same to a loading station, a flap-opener movable toward and from the course of the envelopes, means for conveying the loaded envelopes longitudinally from the loading station, movable mechanism thereafter operating upon the flaps of the envelopes, and driving means and operating connections for operating said floor mechanisms, flap-opener and flap mechanism in timed relation.
43. In a mailing machine, the combination of envelope and enclosure magazines, movable floor mechanisms for said magazines for starting the envelopes and enclosures alternately on their courses, means for conveying the same to a loading station, a flap-opener movable toward and from the course of the envelopes, means for conveying the loaded envelopes longitudinally from the loading station to a flap-inserting station, an inserter at said station comprising spreading and tucking fingers, and driving means and operating connections for operating said floor mechanisms, flap-opener, flap mechanism and inserter in timed relation.
44. In a mailing machine, the combination of envelope and enclosure magazines, movable floor mechanisms for said magazines for starting the envelopes and enclosures alternately on their courses, means for conveying the same to a loading station, a flap-opener movable toward and from the course of the envelopes, means for conveying the loaded envelopes longitudinally from the loading station, movable mechanism thereafter operating upon the flaps of the envelopes, an ejector, and driving means and operating connections for operating said floor mechanisms, flap-opener and flap-mechanism in timed relation.

BEST AVAILABLE COPY

45. A machine of the character described, comprising envelope and enclosure magazines at opposite sides, means whereby the envelopes and enclosures are alternately withdrawn from the bottoms of the stacks and carried inward to the center and there downward to a loading station where the envelopes enter the envelopes, characterized by means at the loading station whereby the fronts of the envelopes are buckled to open their mouths for the reception of the enclosures.

FLORENCE McCARTHY.
